UNITED STATES PATENT OFFICE.

WILLIAM G. BOSWORTH, OF NEW YORK, N. Y., ASSIGNOR TO UNDERWOOD TYPE-WRITER COMPANY, OF NEW YORK, N. Y., A CORPORATION OF DELAWARE.

TYPEWRITING MACHINE.

Application filed December 24, 1923. Serial No. 682,398.

This invention relates to releasable connections between the line-space wheel and the platen in a typewriting machine, arranged to enable the platen to be rotated any desired amount greater or less than a line-space movement without disturbing the line-space wheel.

Devices of this character usually comprise friction clutch-members arranged to be operated by a finger-piece or handle through pressure-multiplying means to move under high pressure into firm gripping engagement with the line-space wheel. It is desirable that the clutch-actuating handle have only a short movement, and, as a result of the shortness of this movement and of the pressure-multiplying connections, the range of movement of the clutch-members is very short, indeed. The clutch mechanism is required, therefore, to be made with extreme precision in order to function properly, that is, in order to cause the clutch-members to grip the line-space wheel firmly and with substantially equal force when moved to effective position, and to completely release the line-space wheel when moved only a short distance to ineffective position. The members, moreover, are subject to wear, and are therefore apt to operate defectively after they have been in use for a while.

In accordance with one feature of the present invention, the need for this extreme precision in the manufacture of the clutch mechanism is eliminated. The clutch-assembly is so constructed and arranged that the clutch-members, when fully assembled, may be adjusted quickly and easily to the proper operating relation in the assembly from the exterior thereof, and this by the operation of a single, very simple, adjusting device. To this end, the clutch-members may consist of outwardly-extending arms forming, in effect, a toggle. The inner ends of the arms abut against a plunger, or abut each other within a slot in the plunger, which may be moved in a direction partially to straighten the toggle and thereby to force the outer ends of the arms into powerful gripping engagement with the line-space wheel. The plunger is arranged to be operated by a cam forming one arm of an operating lever, which is pivoted in a support that may be adjusted from the exterior of the assembly

to adjust the cam toward and from the plunger, so that the adjusted cam, when swung about its pivot, may be caused to produce the desired gripping co-action between the clutch-members and the line-space wheel, regardless of the exact size of the clutch-arms, the plunger, the cam, the line-space wheel, etc. The adjustable cam-support preferably consists of a plug or bushing threaded into a socket in an enlarged end of the platen-axle. It will be seen that the cam, and therefore the operating range of the clutch-members, may be very finely adjusted by the turning of the plug, and that there will be no tendency for the force exerted by the cam to displace the plug.

The cam is arranged to be moved to or slightly beyond a dead-center position to lock the plunger and the clutch-arms positively in effective position. The locking of the clutch-arms in effective condition does not, therefore, depend upon a straightening of the toggle formed by them. The arms are made, in fact, of such length that they become effective when the toggle has been only partially straightened. The clutch may, therefore, be adjusted again and again as the ends of the clutch-arms wear away without its being necessary to replace said arms with new ones, as would be the case each time a little wear occurred if the arms were required to be straightened.

The pressure multiplication effected by this arrangement of the plunger and toggle-arms is considerably less than that which would result from a full straightening of the toggle. This deficiency is more than compensated for, however, by arranging the cam-lever to transmit the force applied to its handle, with multiplied effect. The cam and plunger, therefore, in addition to locking the toggle-arms effective in their partially straightened condition, form also auxiliary pressure-multiplying means. The combined effect of the cam and the toggle enables a high pressure to be exerted by the clutch-arms upon the application of a very moderate force to the clutch-operating handle.

Heretofore platen-clutches employing the principle of straightening out a toggle-linkage have depended upon large coacting sur-

face areas to create a frictional resistance under the pressure from the toggle. Surface contacts of this character provide a self-locking clutch when the toggle is at a dead-center position, and require considerable manual force to break the toggle in releasing the clutch. Furthermore, a frictional engagement or contact is not recognized as a positive means to transmit power.

10 Another feature of the present invention provides a non-self-locking toggle by conditioning diametrically-disposed clutch-arms to become effective at a point in advance of a dead-center position, and which

15 point will be predetermined by the angular coaction between the clutch-arms and the ratchet-wheel, and from which point the clutch-arms will automatically release themselves. The outer end of each clutch-arm is

20 beveled or backed off so that there will be no flat surface on the arms to engage with the ratchet-wheel, but the knife-edge, which is formed with an angle of less than 90°, may be forced into biting engagement with

25 an internal square corner of 90° formed at the juncture of the clutch-drum to the face of the ratchet-wheel. This knife-edge formation not only provides for a positive driving clutch connection between the line-space

30 wheel and the platen-shaft, but also permits the instant release of the clutch due to the absence of surface friction between the arms and the wheel when the pressure against the arms is manually removed. The

35 inner ends of the clutch-arms may be similarly backed off, and the knife-edges so formed may be slightly rounded to facilitate a rocking non-cutting movement of the arms at the points of engagement with the plunger, to reduce frictional contact to a minimum.

It may be that the clutch-arms will be of slightly different lengths, or that some other part of the clutch will be unsymmetrically made, which would cause the arms to tend to grip the line-space wheel unequally. In accordance with a feature disclosed in one form of the invention, imperfect operation due to such irregularity of construction is obviated. The plunger is slotted through to receive the inner ends of the clutch-arms and to permit them to abut against each other. The clutch-arms, however, are unconnected to the plunger or to each other.

50 By this construction the pressure exerted by each of the arms depends upon resistance being opposed to the outward movement of the other, and hence the plunger and clutch-arms form a pressure-equalizing train from

55 the operating lever to transmit the pressure substantially equally through the arms to cause the arms to grip the line-space wheel with equal force.

It is a feature of the invention that the

60 be moved transversely of the platen and hence in a direction not tending to disturb the letter-space position of the carriage.

By arranging the clutch-operating mechanism within the platen-axle, a very simple 70 and efficient construction is obtained. The number and the sizes of the operating parts are reduced. The direct and re-acting forces involved in operating the clutch are 75 fully taken care of in the platen-axle itself, without any tendency to strain or displace other parts held insecurely to the platen-axle.

80 Other features and advantages will hereinafter appear.

In the accompanying drawings,

85 Figure 1 is a front elevation, partly in section, of a part of a typewriting machine having the present improvements applied thereto; the clutch being shown in its effective condition.

Figure 2 is a vertical section on the line 2—2 of Figure 1, looking in the direction of the arrows.

90 Figure 3 is a view similar to Figure 1, but showing the clutch ineffective.

95 Figure 4 is a side elevation of the platen-frame and the clutch-assembly, the cover plate of the platen-frame being removed.

Figure 5 is a detail perspective showing 100 parts of the clutch-assembly separated from each other.

Figure 6 is a detail perspective showing the clutch-arms, plunger and plunger-spring separated from each other.

105 Figure 7 is a vertical section similar to the sectioned portion of Figure 3, showing a form of the invention different from that disclosed in Figures 1 to 6; the clutch being ineffective.

110 Figure 8 is a vertical section on the line 8—8 of Figure 7, looking in the direction of the arrows.

The machine, which may be of the Underwood type, comprises a platen 10 made fast to its axle 11 by screws 12 and journaled by means of said axle in a platen-frame 13, mounted in a traveling carriage (not shown). The line-space lever (not shown) is arranged for operation to engage and thrust to the rear a line-space slide 14, which carries a pawl 15 to engage the ratchet-teeth 16 of a line-space wheel 17, normally fast to the platen-axle 11, for imparting line-space movements of definite extent to the platen 10. A detent 18^a is pressed by a spring 19^a against the ratchet-teeth 16 to engage between successive teeth to assist in controlling the exact line-space position of the platen 10.

115 It is sometimes desirable to rotate the platen 10 more or less than a whole number of line-spaces, and this without disturbing the position of the line-space wheel 17, so that the regular line-feeding of the platen 120

may be resumed immediately after such irregular feeding movement. There is accordingly provided a clutch operable to effect a firm driving connection between the line-space wheel 17 and the platen 10 or to completely disconnect them at the will of the operator.

The line-space wheel 17 includes a hub portion 18 and a drum 19 which comprises an annular flange 20 forming a clutch element fast to the line-space wheel. The platen-axle 11 is enlarged at its left end by stages, the first enlargement 21 being larger than the axle proper, the second enlargement 22 being larger than the first enlargement 21, and the third or outermost enlargement 23 being the largest of all. The line-space wheel 17 is journaled by its hub portion 18 upon the first enlargement 21, and has a vertical wall 24 engaged by the shoulder 25 formed at the inner end of the second enlargement 22. A retaining nut 26 is threaded onto the axle 11 to prevent longitudinal movement of the line-space wheel 17 thereon. Clutch-arms or dogs 27 extend through radial slots 28 in the second enlargement 22 into recesses 29 formed in a plunger 30 and having shoulders 31 and 32 at their outer and inner ends. The plunger 30 is slideable in a bore 33 in the center of the enlargements 21 and 22 of the platen-axle 11.

The clutch-arms 27 are conditioned to effect a clutching engagement within the drum 19 by a toggle action which becomes effective at a point in advance of a straightened-out or dead-center position. Contrary to prior forms of toggle-actuated platen-clutches, frictional surface contact between the clutching elements is avoided. The ends 35 of both arms 27 are beveled or backed off to provide for knife-edge formations at each end thereof, the outer knife-edge of each arm diametrically engaging the drum 19, and the inner ends engaging the end face 31 of the recess 29 and the plunger 30. When the arms 27 are in clutching relation with the line-space wheel as shown in Figure 1, a line drawn diagonally through an arm to bisect both knife-edges gives an angle of approximately 30° removed from a dead-center position. The outer knife-edge of each arm is forced to bite into the square corner of the drum 19—20 and has the same curvature as the inner face of the drum. The inner ends 55 of the arms are fulcrumed at the plunger 30, and these ends may be slightly rounded. As both ends of the arms 27 have only knife-edge contacts, one edge with the drum and the other edge with the plunger, there are no frictional face contacts to retard the withdrawal of the arms the instant pressure is manually removed from the plunger.

The outermost enlargement 23 has a large threaded socket 36 within it, into which is threaded a plug or bushing 37 bearing a

clutch-operating cam-lever 38. The cam-lever 38 consists of a cam 39 mounted on a pivot-pin 40 in the plug 37, the pivot-pin extending at right angles to the platen-axle 11, and an operating handle or finger-piece 41 for the cam 39. The finger-piece 41 is operable in a slot 42 in the plug 37, being limited in its ineffective position by engagement with the end wall 43 of the slot 42, and in its effective position by engagement with the end wall 44 of the slot 42. In this latter position, the cam 39 is slightly beyond the dead-center position, and hence serves to lock the clutch in effective condition. In this position, the finger-piece 41 is substantially in alignment with the axis of the platen 10, and does not, therefore, have any substantial movement at the rotation of the platen, so that it can be readily found by the operator in any rotated position of the platen. The finger-piece 41 extends slightly beyond the left platen-turning knob 45, and hence will necessarily be engaged by the operator's hand when the platen-knob is seized to rotate the platen. In order to avoid injury to the hand of the operator, the finger-piece is substantially spherical at its outer end 46, but, in order to assist the operator in determining the direction in which the finger-piece should be moved to render the clutch ineffective, smooth and rough flats 47 and 48 are provided on the spherical portion, one of which will always be in the view of the operator. These flats also enable the operator to grip the end 46 without slipping.

Naturally the heavy end 47 will vibrate by gravity at each revolution of the platen when the clutch-elements are in a released state as shown in Figure 3. To prevent such vibration and to remove any rubbing contact between the arms 27 and the drum 19, a light coil-spring 34 may be seated within the end of the bore 33 to press against the end of the plunger 30 to prevent idle vibration of the lever 41 from the position in Figure 3 when the platen is rotated independently of the ratchet-wheel.

In assembling the device, the plunger-spring 34 and the plunger 30 are placed in the bore 33 and the clutch-arms 27 are inserted through the slots 28. The line-space wheel 17 is then put in place on the platen-axle 11, and is secured against end-wise movement thereon by the retaining nut 26. The plug or bushing 37 is then threaded into the socket 36. In performing this last step, the correct adjustment of the plug 37 may be quickly determined by placing the finger-piece 41 in position to hold the clutch effective, that is, in the position shown in Figure 1, and by using it as a handle to turn the plug. When the plug 37 has been turned just as far as possible in this manner, it will be found that the clutch is securely locked and that the movement of the finger-piece 41 about the

- 5 pivot 40 to render the clutch ineffective, as seen in Figure 3, will permit the clutch-arms 27 to be completely disengaged from the drum 19, so that the platen-axle may rotate freely with respect thereto. A retaining screw 49, threaded through the platen-turning knob 45 and the enlargement 23, to bear against the plug 37, may now be tightened to prevent accidental rotation of the plug. The 10 platen-axle 11 is then passed through the platen-frame 13 and the platen 10, and is secured to the latter by the screws 12. A platen-turning knob 50 is then secured upon the platen-axle 11 by screws 51. It will be 15 seen that, in order to again adjust the clutch when the arms 27 or the drum 19 has become worn, it is only necessary to loosen the retaining screw 49 and turn the plug 37 in the manner just described.
- 20 In Figures 7 and 8 a form of the invention is disclosed which is different in an important respect from the form shown in Figures 1 to 6, and heretofore described. This form is the same as that already described 25 in every respect, except that the plunger 30' has a slot 52 extending through it to receive the clutch-arms 27' and permit them to be arranged with their inner ends in abutting and supporting relation to each other. 30 These clutch-arms 27' are unconnected to the plunger 30', or to each other, and hence the plunger and arms form pressure distributing and equalizing means for transmitting the pressure of the cam 39 equally to the outer 35 ends of the arms 27', so that they will be caused to grip the drum 19 with equal force, even though they may be of slightly different lengths, or other parts of the clutch may be arranged in an unsymmetrical manner.
- 40 Variations may be restored to within the scope of the invention, and portions of the improvements may be used without others.
- Having thus described my invention, I claim:
- 45 1. In a typewriting machine, the combination of a platen and a platen-shaft, a line-space wheel loose on the shaft and formed with a clutch-drum, a detent for the line-space wheel, a pair of rigid, co-operative, loose, separately-mounted, nipping, radial clutch-arms having knife edges, said arms being over-length to serve as self-opening toggle-elements and opposed to each other, and self-locking manual means operable upon 50 both arms to force them radially into nipping engagement with the drum, said arms mounted at their inner ends to form a self-equalizing toggle within the drum.
- 60 2. In a typewriting machine, the combination with a revoluble platen and a line-space wheel, of a bearing member for the line-space wheel, said member being fast to the platen and having an axially-extending bore and radial slots extending outward from the bore, a plunger slidable in said bore, clutch-arms extending through the slots and engaging the 65 plunger, said arms being arranged to be

forced outward into clutching engagement with the line-space wheel by movement of the plunger in one direction, and to be released by movement of the plunger in the reverse direction, a plug threaded into the outer end of said bearing member, and a plunger-operating finger-piece pivoted in the plug, the arrangement being such that the plug can be turned to adjust the position of the finger-piece, and so to adjust the range of movement of the clutch-arms, to assure perfect gripping of the clutch in effective position and complete disengagement of the clutch in ineffective position.

3. In a typewriting machine, the combination of a platen and a platen-shaft, a line-space wheel loose on the shaft and formed with a clutch-drum, a detent for the line-space wheel, a pair of rigid, co-operative, loose, separately-mounted, nipping, radial clutch-arms having knife edges, said arms being over-length to serve as self-opening toggle-elements and opposed to each other, a plunger to guide and push both of the clutch-arms into nipping engagement with the line-space wheel, and manual means operable to apply pressure to the plunger.

4. In a typewriting machine, the combination of a platen and a platen-shaft, a finger-wheel for the platen, a line-space wheel loose on the shaft and formed with a clutch-drum, a detent for the line-space wheel, a pair of rigid, co-operative, loose, separately-mounted, nipping, radial clutch-arms having knife edges, said arms being over-length to serve as self-opening toggle-elements and opposed to each other, a central, slidable element provided with means to force the arms radially into nipping diagonal engagement with the line-space wheel, and means rotatable with the finger-wheel and operative independently thereof to actuate the sliding element.

5. In a typewriting machine, the combination of a platen and a platen-shaft, a line-space wheel loose on the shaft and formed with a clutch-drum, a detent for the line-space wheel, a pair of rigid, co-operative, loose, separately-mounted, nipping, radial clutch-arms having knife edges, said arms being over-length to serve as self-opening toggle-elements and opposed to each other, and self-locking manual means operable upon both arms to force them radially into nipping engagement with the drum, said arms mounted at their inner ends to form a self-equalizing toggle within the drum.

6. In a typewriting machine, the combination with a revoluble platen and a line-space wheel therefor, of a line-space wheel support fast to the platen, a platen-turning knob fast to the support, and means for clutching the line-space wheel to its support, comprising a pivoted finger-piece extending from the support beyond the platen-turning

knob, the finger-piece being round to prevent the operator's injuring his hand upon it when rotating the platen-turning knob, and having rough and smooth flats at opposite sides to indicate to the operator the direction in which the finger-piece should be moved to operate the clutch.

7. In a typewriting machine, the combination of a platen and a platen-shaft, a line-space wheel loose on the shaft and formed with a clutch-drum, a detent for the line-space wheel, a pair of rigid, co-operative, loose, separately-mounted, nipping, radial clutch-arms having knife edges, said arms being over-length to serve as self-opening toggle-elements and opposed to each other, a central plunger to guide the clutch-arms and support their inner ends to effect the toggle movement, and manual means operating to engage the plunger.

8. In a typewriting machine, the combination of a platen and a platen-shaft, a line-space wheel, a detent therefor, a finger-knob for rotating the platen independently of said line-space wheel, a non-self-locking clutch including a pair of loose, diametrically-expansible, rigid, sharpened, nipping, opposite, toggle-acting clutch-arms, a slideable, central element provided with means to expand the clutch-arms radially into nipping engagements with the line-space wheel, and means rotatable with the finger-knob and operable independently thereof to actuate the sliding element.

35 9. In a typewriting machine, the combination with a revoluble platen and a line-space wheel therefor, of means for effecting driving connection between the line-space wheel and the platen, comprising clutching members, a common operating means for said members, a cam movable in engagement with said operating means to make the clutching members effective to grip the line-space wheel, and means for adjusting the position of the cam for varying the effect on the clutching members produced by its operation.

10. In a typewriting machine, the combination with a revoluble platen and a line-space wheel therefor, of a line-space wheel support fast to the platen and having an axially-extending bore and radial slots extending out from the bore, a slotted plunger slideable in said bore, diametrically-arranged clutch-arms extending through said slots in the support-member and into abutting engagement with each other within the slot in the plunger, and means for moving the plunger to force the arms outward into clutching engagement with the line-space wheel, the arms, by reason of their abutting relation to each other, acting with equal pressure against the line-space wheel.

11. In a typewriting machine, the combination of a platen and a line-space wheel

therefor, a support for the line-space wheel fast to the platen, means for effecting a positive driving connection between the line-space wheel and its support including a pair of diametrically-disposed knife-edged clutch-arms, supported and operable to diagonally engage the line-space wheel under a clutch-producing pressure, and an adjusting device to predetermine the pressure to be applied to the clutch-arms.

12. In a typewriting machine, the combination with a revoluble platen and a line-space wheel therefor, of a line-space wheel support fast to the platen, a finger-piece mounted on the support, and a clutch operated by the finger-piece for making the line-space wheel fast to its support, said clutch comprising a plurality of sharpened, loose, opposed toggle-members movable into nipping engagement with the line-space wheel, means being provided for automatically equalizing the nipping pressure exerted by said members, manual means to operate the toggle, and a single adjusting device operable to change the nipping force exerted by said members.

13. In a typewriting machine, the combination with a platen and a line-space ratchet-wheel for the platen co-axial therewith, of a platen-axle fast to the platen, and means for effecting a driving connection between the line-space ratchet-wheel and the platen-axle, comprising a drum fast to the line-space ratchet-wheel, a pair of toggle arms positively driven by the platen-axle but unconnected thereto, a slide movable in the direction of the axis of the platen to press against the inner ends of the toggle arms and thereby force their outer ends outward into gripping engagement with the drum, and a spring for flexing the toggle to make the arms ineffective, the toggle arms being unconnected to the slide and being therefore free to rock about their outer ends in moving to ineffective position, and the outer ends of the arms being rounded to prevent binding and to facilitate such rocking movement.

14. In a typewriting machine, the combination with a platen and a line-space ratchet-wheel for the platen co-axial therewith, of a platen-axle fast to the platen, and means for effecting a driving connection between the line-space ratchet-wheel and the platen-axle, comprising a drum fast to the line-space ratchet-wheel, a pair of toggle arms positively driven by the platen-axle but unconnected thereto, a slide movable in the direction of the axis of the platen to press against the inner ends of the toggle arms to partially straighten the toggle and thereby force the outer ends of the arms outward into gripping engagement with the drum, means for positively locking the arms in effective gripping position, and a spring for flexing the toggle when the arms are released by the

locking means, the arrangement being such that the arms can be easily moved from effective position by the spring, due to the fact that the toggle formed by them is only 5 partially straightened when effective.

15. In a typewriting machine, the combination with a platen and a line-space ratchet-wheel for the platen co-axial therewith, of a platen-axle fast to the platen, and means 10 for effecting a driving connection between the line-space ratchet-wheel and the platen-axle, comprising a drum fast to the ratchet-wheel, a pair of toggle arms positively driven by the platen-axle, a toggle-operating 15 member movable in a direction to straighten the toggle to force the toggle arms outward into gripping engagement with the drum, the arms being of such length that they grip the drum and are arrested by it when the 20 toggle is only partially straightened, the toggle arrangement serving to multiply the force exerted by the toggle-operating member, and a cam lever for actuating the toggle-operating member, the cam lever comprising a handle arm and a cam arm and being arranged to transmit to the toggle-operating member with multiplied effect the force applied to the handle arm.

16. In a typewriting machine, the combination with a platen and a line-space ratchet-wheel for the platen co-axial therewith, of a platen-axle fast to the platen, and means for effecting a driving connection between the line-space ratchet-wheel and the platen-axle, comprising a drum fast to the ratchet-wheel, a pair of toggle arms positively driven by the platen-axle, a toggle-operating member movable in a direction to straighten the toggle to force the toggle arms outward 25 into gripping engagement with the drum, the arms being of such length that they grip the drum and are arrested by it when the toggle is only partially straightened, the toggle arrangement serving to multiply the 30 force exerted by the toggle-operating member, and a cam lever for actuating the toggle-operating member, the cam lever comprising a handle arm and a cam arm and being arranged to lock the toggle-operating member 35 positively in position to maintain the toggle arms in effective gripping relation to the drum.

17. In a typewriting machine, the combination with a platen and a line-space wheel 40 for the platen coaxial therewith, of a line-space-wheel support fast to the platen, means for effecting a positive driving connection between the line-space wheel and the platen, including a pair of diametrically-disposed 45 clutch-arms arranged to become effective

when the toggle formed by them engages with the line-space wheel, a lever pivoted within said support and operative to force both arms into angular clutching engagements with the line-space wheel, and operating 50 connections between the lever and the clutch-arms, including adjustable pressure-multiplying means and positive locking means for retaining the clutch-arms in positive clutching engagement with the line-space wheel.

18. In a typewriting machine, the combination of a platen and a platen-shaft, a line-space wheel loosely mounted upon the shaft and including a drum having an annular interior corner formed therein, a pair of 55 slideable clutch-arms, each arm having knife-edged end-formations and movable to diagonally engage the knife-edge thereof with said corner of the drum, a plunger supporting the inner end of each clutch-arm to expand both arms, and manually-operable camming means to apply pressure to the plunger to force the clutch-arms into positive locking engagement with the corner of the drum only.

19. In a typewriting machine, the combination of a platen and a platen-shaft, a line-space wheel loosely mounted upon the shaft and including a drum having an annular interior corner formed therein, a clutch including a pair of clutch-dogs rotatable with the shaft and diagonally disposed towards the annular corner, the ends of both dogs being backed off to provide a knife-edge-engaging formation, a plunger operatively connected to the inner ends of both dogs to force the outer sharpened ends into engagement with the corner of the drum and positively lock the drum and line-space wheel to the platen-shaft, and manual means operable to actuate and finally lock the plunger.

20. In a typewriting machine, the combination of a platen and a platen-shaft, a line-space ratchet-wheel including a clutch-drum mounted for a free movement on said shaft, a detent for the ratchet-wheel, a finger-wheel permanently secured to the platen-shaft to rotate the platen, a clutch including a pair of clutch-arms diametrically related to each other to effect a toggle-clutching engagement within said drum under pressure and be automatically self-opening when the pressure is removed, a plunger operable to diagonally expand the clutch-arms, and a manually-operable pivoted cam to operate the plunger to expand the clutch-arms and positively hold the expanded arms under pressure.

WILLIAM G. BOSWORTH.
